Primary Examiner — Jae Liang*Assistant Examiner* — Tia Ruth-Renee Polidori(74) Attorney, Agent, or Firm — Banner & Witcoff, Ltd.(57) CLAIM

The ornamental design for a tumbler, as shown and described.

DESCRIPTION

FIG. 1 is a top, front, right perspective view of a tumbler showing our new design;

FIG. 2 is a top, rear, left perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof; and,

FIG. 9 is a top, front, right perspective view of a tumbler showing our design in an alternate configuration.

The broken lines illustrate portions of the tumbler that form no part of the claimed design.

1 Claim, 8 Drawing Sheets# US D982,982 S
